UNITED STATES PATENT OFFICE.

OSCAR C. DAVIS, OF BROCKTON, MASSACHUSETTS, ASSIGNOR OF ONE-HALF TO GEORGE E. KEITH, OF BROCKTON, MASSACHUSETTS.

WELT-STRIP.

1,169,085.

Specification of Letters Patent. Patented Jan. 18, 1916.

Application filed October 9, 1914. Serial No. 865,793.

To all whom it may concern:

Be it known that I, OSCAR C. DAVIS, a citizen of the United States, and resident of Brockton, in the county of Plymouth and State of Massachusetts, have invented 5 certain new and useful Improvements in Welt-Strips, of which the following is a specification:

In the manufacture of boots and shoes it 10 is customary to "indent" or "prick" the sole extension after the sole has been stitched to the shoe. In welt shoes the "indenting" or "pricking" is performed on the welt. This 15 operation of indenting or pricking involves loss of time because it has hitherto required a separate operation.

The object of the present invention is to 20 obtain the same result without any special operation, without any additional handling 25 of the shoe, and without any loss of time incidental to obtaining such result. I accomplish this end by molding indentations in or embossed portions on a welt strip of suitable material before the welt strip is attached to the shoe. In order to form the indentations or embossed portions by molding, it is of course necessary to make the 30 welt strip of some material capable of being molded, and I have anticipated this requirement by conceiving the idea of making the welt strip of rubber or any other moldable material, which if necessary may have embedded in it suitable reinforcing material such as canvas or duck. I have illustrated 35 and described such a welt strip in my copending application Serial No. 861,468, filed September 12, 1914. The molds which are used to form the rubber as used in the welt strip shown in the said copending applica-

40 tion are provided with ribs or grooves or other indentations or projections whereby any desired design of indenting or embossing may be imparted to the welt strip at the time of molding the same, and the addition 45 of such portions to the mold would not add materially to the cost of making welt strips, whereas it would save a considerable amount of dispensing with the necessity of performing an additional operation.

50 Of the accompanying drawings: Figures 1, 2 and 3 represent in perspective short pieces of welt strips having grooves of different arrangements whereby different designs or visual effects are produced. These 55 examples are merely suggestive and do not

represent any attempt to show all the different arrangements or designs which can be produced. It may be explained that in the original drawings the scale is larger than the actual articles. In these figures 60 respectively a welt strip is indicated at a' , a^2 , a^3 , and a stitch-receiving groove b is formed therein, on the under side, to receive the inseam stitches. Grooves c are formed in the outer marginal portions, such grooves 65 being molded during the process of vulcanization. The various designs produced by the various arrangements of grooves are immaterial so far as the fundamental principle is concerned. In Figs. 1, 2 and 3 the 70 grooves are in the form of grooves and are parallel. A welt strip which is so grooved prior to being attached to a shoe may be more readily curved to fit the curvatures of a shoe than one which has no grooves at the 75 time of being attached, the relatively thin portions of the strip produced by the grooves enabling the outer marginal portion to be more easily stretched or contracted, as the case may be, when attaching the strip 80 to a shoe.

In the form shown by Fig. 4 the strip is indicated at a^4 , and the top face thereof has embossed portions c' in the form of ribs. The shape and arrangement of the embossed portions may be varied as desired. 85

Fig. 5 represents a cross section of a welt strip such as a' , a^2 , a^3 , in a plane corresponding to that indicated by line 5—5 of Fig. 1. Fig. 5 shows a reinforcing element 90 d such as a layer of woven fabric, the same being illustrated, described and claimed in the aforesaid application, Serial No. 861,468.

All the modifications shown are alike in 95 the following respects: Each has a plain longitudinal marginal portion a on the top face. This plain marginal portion receives the inseam stitches, being located with reference to the groove b with this end in view. When the welt strip is incorporated into a 100 shoe the plain marginal portion a lies in contact with the shoe upper, as will readily be understood by anyone who understands shoe making. The grooves c or embossed portions c' , as the case may be, are purposely omitted along the marginal portion a to prevent the formation of channels through which water could pass when the 105 welt strip is attached to a shoe. In other 110

words, the formation of grooves or ribs along the outer marginal portion of the welt strip does not cause channels through the inseam of the finished shoe, the contact 5 between the plain marginal portion *a* and the shoe upper being continuous and as effective for excluding water as though the welt strip had no irregularities in its top surface. Another feature common to all 10 the forms shown is that the outer marginal portion of the strip has alternate thick and thin portions, regardless of whether the thin portions are the result of grooves or whether the thick portions are the result of ribs. 15 Inasmuch as the stitch-receiving groove *b* which receives the inseam stitches is necessarily near the inner edge of the welt strip, it might unduly weaken the strip to continue the grooves *c* to the inner edge, for in 20 that case the inner marginal portion of the strip would be grooved on both sides.

I claim:

1. An article of manufacture consisting of a welt strip composed of rubber, one side 25 of said strip having a plain upper-engaging marginal surface and a series of transversely extending molded grooves, the opposite side of said strip having a longitudinally extending molded stitch-receiving groove. 30
2. An article of manufacture consisting of a welt strip composed of rubber, and reinforcing means embedded therein, one longitudinal marginal portion of said strip 35 having a plain upper-engaging surface on one side and a longitudinally extending molded stitch-receiving groove in the opposite side, said reinforcing means being arranged to receive stitches sewn in said 40 groove, the body of said strip having a se-

ries of transversely extending molded grooves in said one side.

3. An article of manufacture consisting of a welt strip composed of rubber, and reinforcing means embedded therein, one longitudinal marginal portion of said strip having a plain upper-engaging surface on one side and a longitudinally extending molded stitch-receiving groove in the opposite side, the body of said strip having a 45 series of transversely extending molded grooves in said one side, said reinforcing means being arranged to receive the stitches sewn through said body portion. 50

4. An article of manufacture consisting of a welt strip composed of rubber, and reinforcing means embedded therein, one side of said strip having a longitudinally extending molded stitch-receiving groove in one marginal portion and a plain sole-engaging surface on the opposite marginal portion, the opposite side of said strip having a plain upper-engaging surface on said one marginal portion and a series of transversely extending molded grooves in said 60 opposite marginal portion. 65

5. An article of manufacture consisting of a molded welt strip composed of rubber, and reinforcing means embedded therein, the upper-engaging side of said strip having a smooth molded inner marginal portion and a corrugated molded outer marginal portion. 70

In testimony whereof I have affixed my signature, in presence of two witnesses.

OSCAR C. DAVIS.
